Horace Bartlett, inventor & manufacturer

Letters Patent.

The schedule referred to in these Letters Patent and making part of the same containing a description in the words of the said Horace Bartlett, himself, of his improvement in the cooking stove.

To all to whom these presents shall come,
Be it known that I, Horace Bartlett, of Carmel, in the County of Putnam and State of New York, have invented a new & useful improvement in the form and construction of my patent stove ad cooking stove, and that the following is a full and exact description of the construction and operation of the said cooking stove as invented or improved by me. The base for the fire is across the stove from front to rear, see plate cl. 1, letter A, a plate forming the remaining part of the bottom, tressing in a horizontal form. From the top of this bed to the full length of the stove, which, for the sake of description, I call the wings see plate cl. 1, Plate cl. 3, forms the bottom of the oven, over the bed for the fire or plate cl. 1, in between these plates the blaze is crimped suddenly off, forming thereby a more powerful draft. This 'tis plate, in the bottom of the oven, and back of the main body of the stove, are holes for boiler plates cl. 8 letter b, at each corner of this plate, is a hole for the smoke, over which stands a pipe, in the form of a half circle, letter C, below these pipes, connected with them in a circular form, is a piece forming the end of the stove. Having these pipes is a piece forming the length of the oven, leaving an opening for the smoke, letter d, upon the top of these pipes is a plate forming the top of the oven, plated cl. 3, over this is another, raised higher, forming what I call the damper plate cl. 4, through which, at each end, is a hole for boiler plates cl. 8, the back part of this damper extends the pipe letter f through the bottom plate of the oven, which forms the top of the oven,

in whole lottery: this covering the door into the chimney, when in
boiling; when baking, this is closed by a damper on the under
side of the plates between these plates i.e. the inside of the
drum are the dampers, see sketch, plated. S. doors opening from
the outside. What I claim as an improvement, is extending
the bed for the fire, back of the main body of the stove.
What I claim as new, and a useful invention
to community, is, extending the bed for the fire so far
back, that it receives long wood, and only about one half
of it is burning at a time, unless the draft door is opened at
the back end, which may be done, when more heat is required
thus putting in long wood, leaving it perfectly under the
control of its manager, consuming no more than what is
required for immediate use; thereby saving the expense
of cutting the wood into short pieces; acting something on
the principle of burning coal from the base; but this being
in a horizontal form, I believe to be new and never
before used to my knowledge, when applied to wood
for a baking stove.
